Primary Examiner — John R Yeh(74) *Attorney, Agent, or Firm* — Rankin, Hill & Clark LLP(57) **CLAIM**

The ornamental design for a shoe cleaning device, as shown and described.

DESCRIPTION

FIG. 1 is a front, right side perspective of my design for a shoe cleaning device in an open configuration;
FIG. 2 is a top view thereof;
FIG. 3 is a bottom view thereof;
FIG. 4 is a right side view thereof;
FIG. 5 is a left side view thereof;
FIG. 6 is a front view thereof;
FIG. 7 is a rear view thereof; and,
FIG. 8 is a rear, right side perspective view illustrating the device in a partially closed configuration.

1 Claim, 6 Drawing Sheets(56)
